APPARATUS FOR FINISHING SHEETS

Ray M. Fenton, Youngstown, Ohio, assignor to
The Newton Steel Company, Youngstown, Ohio,
a corporation of Ohio

Application July 7, 1930, Serial No. 466,147

1 Claim. (Cl. 29—17)

This invention, relating as indicated to apparatus for finishing sheets, has particular reference to apparatus which is adapted to receive sheets after the same have been properly rolled in the hot mills, such apparatus being designed to accomplish every step in the finishing process for the sheets as the same pass through the apparatus continuously after leaving the hot mills.

The usual rolling mill practice for finishing sheets has been to manually transfer the sheets which are usually arranged in packs from and to the several machines which are employed for the purpose of finishing such sheets, such practice resulting in a greater cost of finished product than that which is obtained by the employment of the apparatus comprising my invention. More specifically my invention contemplates the arrangement of the several machines which are usually employed for the purpose of finishing the sheets in longitudinal alignment so that, as the sheets are discharged either from the hot rolls or other apparatus, and from the several units included in my apparatus, the same are received in proper alignment by the next succeeding unit, so that the sheets may pass through the entire finishing line continuously and successively without any loss of time or manual handling, such as has heretofore been employed. The longitudinal alignment of the several machines comprising my invention makes possible the synchronization of such units so that the proper speed of the sheet or sheets may be produced as the same are fed to or through the several units of the apparatus. This advantage of control over the rate of travel of the sheet increases the efficiency of the several units to a maximum, and further expedites the handling of such sheets, so that a maximum amount of production is obtained from a minimum of apparatus.

Another primary advantage of the apparatus comprising my invention resides in the efficiency of its operation without the necessity of personal supervision on the part of an operator or operators. When the sheets have once been started through the apparatus after having been discharged from the hot rolls, or normalizing furnace, etc., no further personal attention to the finishing operation is necessary until the sheets have been discharged from the finishing apparatus and stacked. It is among the objects of my invention to provide an apparatus for finishing sheets which shall have all of the above named desirable characteristics. Other objects of my invention will appear as the description proceeds.

To the accomplishment of the foregoing and re-

lated ends, said invention, then, consists of the means hereinafter fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:

Fig. 1 is a plan view of the apparatus comprising my invention; and Fig. 2 is a diagrammatic elevational view showing the co-relation of the several units.

Referring more specifically to the drawing, the sheets to be finished are discharged either singly or in packs from the hot rolls or normalizing furnace, or other suitable apparatus, into a pickling apparatus 1, which may either be of the batch or continuous type, as is well known to those familiar with the art of rolling mill procedure. Positioned in longitudinal alignment with the pickler is a scrubbing machine 2 which may be of any well known form of construction, here illustrated as consisting of a plurality of rolls 3 which are in driving communication one with the other in a gear box 4 which has a motor 5 in communication therewith for the purpose of driving the several rolls of the scrubbing machine.

After the sheets have passed through the scrubbing rolls 3, they pass through an air dryer 6 which has in communication therewith an air duct 7 leading to a blower 8 which may be driven by a motor 9.

When the sheets leave the air dryer 6 they pass onto a straightening table 10 which consists of a plurality of angularly disposed rolls 11 driven by means of a motor 12 which force such sheets hard over against a longitudinally extending stop 13 which properly lines such sheets preparatory to their introduction to the next unit in the finishing apparatus. The sheets, after having been properly straightened by the straightening table 10, pass through a roller leveller 14 which may be driven by a motor 15. An endless belt conveyor 16 is positioned in longitudinal alignment with the roller leveller 14, such belt being driven through a suitable connection as indicated at 17 from the leveller 14. The conveyor 16 projects the sheets between vertically arranged cold rolls 18 and 19 which, as most clearly illustrated in Fig. 2, may have a pinch roll 20 in association therewith for the purpose of properly feeding the sheets to such rolls to prevent the same from becoming cracked and marred. The cold rolls 18

19 are journalled in the usual manner in housings 21 and 22 and are driven through a gear reducer 23 by means of the motor 24.

5 In longitudinal alignment with the cold rolls 18 and 19 are conveyors 25 and 26 which, although indicated in Fig. 2 as consisting of two separate endless belts, are really in fact parts of the same conveyor which is driven by means of the motor 27. A second set of cold rolls 28 and 29 are positioned adjacent the discharge end of the conveyor 26 and these rolls may likewise have a pinch roll 30 in association therewith for the purpose of insuring the proper feeding of the sheets thereto.

10 A relatively short conveyor 31 receives the sheets from the cold rolls 28 and 29 and projects the same to the dryer positioned in longitudinal alignment therewith, which consists of rolls 32 which move the sheets through an air dryer 33. Preliminary to such drying, however, hot water, 15 or the like, may be projected onto the sheets to facilitate the operation of the hot air dryer 33. The hot air dryer 33 has a hot air conduit 34 in communication therewith which leads from a blower 35 driven by a motor 36. The sheets, 20 after leaving the hot air dryer 33, pass through a suitable roller leveller 37 which is driven by a motor 38. After the sheets leave the leveller 37 they may be stacked or otherwise disposed of 25 having been completely finished in their travel through the above described apparatus.

30 As merely indicative of the several speeds at which the separate units of the apparatus comprising my invention may be driven to effect a properly controlled movement of the sheets 35 through the apparatus, I may prefer to have the linear velocity imparted to the sheets by the rolls of the scrubbing machine 2, approximately one hundred and forty-two (142) feet per minute. The linear velocity of the sheets through the 40 dryer 6 is approximately 160 feet per minute, the speed through the straightening table is 247 feet per minute, the linear velocity of the rolls of the roller leveller 14 is approximately 141 feet per minute, the linear velocity of the endless 45 conveyor 16 is approximately 310 feet per minute, the tangential velocity of the cold rolls 18 and 19 and 28 and 29 is approximately 306 feet per minute. The linear velocity of the endless conveyor 25 and 26 is approximately 310 feet 50 per minute, the linear velocity of the endless conveyor 31 may be approximately 304 feet per minute, the tangential velocity of the rolls 32 may be approximately 190 feet per minute, the tangential velocity of the conveyor moving the sheets through the dryer 33 is approximately 185 feet per minute, and the tangential velocity of 55 the rolls and the roller leveller is approximately

183 feet per minute. The above described speed ratios of the several units which may be maintained at all times by having the proper gear ratio in association with each of the driving motors and having such motors either synchronous or operating from the same potential whereby uniformity of the above speed ratio is at all times maintained.

5 By employing the above described apparatus, it will be noted by those familiar with the art of 10 finishing sheet metal, that the sheets may be quickly and very economically given their final finish preparatory to shipment or consummation at a minimum cost and with a reduction in the number of scrap sheets far below that accomplished by any apparatus heretofore employed.

15 It will be noted by those familiar with the art of sheet metal manufacture that I have employed several units such as the straightening table and the first roller leveller in the finishing line 20 through which the sheets must pass, which units have heretofore never been employed inasmuch as the form of my improved apparatus is such that these units are essential to prepare the sheets so as to be capable of being mechanically 25 fed to the cold rolls which are positioned later in the finishing line.

20 Other modes of applying the principle of my invention may be employed instead of the one explained, change being made as regards the 30 mechanism herein disclosed, provided the means stated by the following claim or the equivalent of such stated means be employed.

25 I therefore particularly point out and distinctly claim as my invention:

30 In a machine for automatically imparting a full finish to steel sheets, in combination, a continuous pickler; a scrubber, a dryer, and a straightener, said scrubber, dryer and straightener being in an operative alignment and adapted 40 to receive sheets automatically from said pickler and advance them through the said devices in the order stated at an increasing rate of speed; a leveller adapted to automatically receive sheets 45 discharged from said straightener; a conveyor, a stand of cold rolls, a second conveyor, a second stand of cold rolls and a discharge conveyor, said conveyors and rolls being synchronized to advance a sheet received from said leveller at a decidedly higher, substantially uniform, speed, a 50 dryer and a leveller, said devices being synchronized to substantially uniform speed materially less than that of the cold rolls, and aligned for the automatic passage of sheets through the several devices in the order named. 55

RAY M. FENTON.
